TURBINE

Francis M. Brooke, Bryn Mawr, Pa., assignor to
Nanna S. Brooke, Bryn Mawr, Pa.

Application March 17, 1933, Serial No. 661,243

4 Claims. (Cl. 253—16.5)

This invention relates to elastic fluid power units, and more particularly to a steam or gas turbine of the double-rotor type.

The primary object of my invention is to shorten the length of such turbines, while utilizing the normal applied effort, by substituting for the stator blades, in an ordinary axial flow turbine, a secondary or double set of rotor blades.

Another object is to increase the efficiency of such a turbine by having rotor blades receive effective effort from the gas, where previously the stator blades only straightened the path of the gas, under the theory that every time a particle strikes a surface the refractory force loses 15 a certain amount of energy consumed by impact.

A further object is to permit the use of gas or steam at a higher velocity than heretofore, with the same degree of safety.

A still further object is to enable lighter construction of turbines, at a given steam or gas velocity, without decrease in efficiency.

The stated objects, with incidental advantages, are attained by the embodiment of my invention illustrated in the accompanying sheets of drawings; while the claims at the conclusion of the following detailed explanation of said drawings, succinctly define the features of novelty over prior art.

Fig. I is a longitudinal section of my improved 30 turbine.

Fig. II is a longitudinal sectional continuation at the left-hand end of Fig. I.

Fig. III is an elevation of the turbine at the exhaust end.

Fig. IV is a fragmentary cross-section of the 35 turbine taken along the line A—A' in Fig. I.

Fig. V is a side elevation of a sprocket-holding cage, hereinafter fully described.

Fig. VI is a parallelogram illustrating the 40 travel of a rotor blade in relation to the travel of the gas in an ordinary turbine.

Fig. VII is a parallelogram illustrating the 45 double rotor travel in relation to the travel of the gas in my improved turbine as hereinafter described.

Fig. VIII illustrates the travel of the gas from a rotor to a stator, to a rotor blade, in an ordinary 50 turbine.

Fig. IX shows the travel of the gas from a rotor to a rotor revolving in the opposite direction, which is used in place of a stator, to a third rotor blade; and,

Fig. X shows the path of two molecules of gas 55 impinging on several rotor blades.

In all the views corresponding reference characters designate the same or similar parts.

Referring to Fig. I, the rotor shaft 1 is supported by end bearings 2, which are held in place by supports 3 that are secured on the base 4. 5 On this shaft 1 is fixed the first rotor which is comprehensively designated 5, to which are fixed rotor blades 7, and which rotates clockwise.

A support 9 holds in position an extension 10 of the manifold inlet pipe 11. The manifold 11 10 and extension 10 are retained in position by bolts 12 and nuts 13 while leakage is prevented by gaskets 14. It may be noted that the extension 10 has spaces 15 for circulation of water, which is conveyed to and from 10 by pipes 16. On the 15 extension 10 is screwed a collar 17, which is adjustable, leaving a space 18 to be filled with packing and thus serving as a stuffing box to prevent leakage.

The outer surface of the collar 17 is a fine 20 bearing surface excepting at the far end from the stuffing box, where it is threaded a convenient distance for fitment of a collar 22. The second rotor, which is comprehensively designated as 6, on which are fastened rotor blades 8, is made in 25 two or more longitudinal sections, not specifically indicated, that are bolted together in accordance with known practice.

In assembling the turbine, the collar 17 is 30 screwed on the extension 10 in approximately the position shown. Shaft 1 with rotor 5 is next placed in position. Collar 17 is screwed to approximately the position shown and the packing is first inserted in space 18. The sections of the 35 second rotor 6 are then bolted together so that blades 8, 7 are spaced between each other as shown. Balls 19 are then placed in position and collar 20 is suitably secured to rotor 6. Collar 22 is then screwed a little distance along the collar 17 and balls 21 inserted, whereupon said collar 40 is screwed sufficiently far along the collar 17 to retain the balls 21 in the groove preparatory to final adjustment.

A large collar 23, after having packing put in 45 the stuffing box space 24 is fixed in the approximate position as shown. Balls 25 are then placed in the groove shown and the collar 26 secured in place to retain said balls 25 in position. Later perfect adjustment is obtained by moving the collars 17, 23, so as to make the packing in spaces 50 24 and 18 tight, whereupon the collars 22 and 26 are manipulated so as to perfectly space the rotor blades 7, 8 of the rotors 5, 6. It may now be noted that rotor 6 can rotate freely on the rotor 55 at the exhaust end of the turbine and on the

extension inlet manifold 10 at the inlet end, furthermore that leakage between the two rotors is effectively stopped by the packings at 18 and 24.

The privilege is reserved of utilizing other than ball bearings, such as smooth roller bearings, etc., rather than annular ball or thrust ball; or the annular contact ball bearing which is used both as a thrust and an annular bearing herein. Furthermore, in both spaces 18 and 24 other than 10 common packing may be used to ensure the most perfect gas fit with a minimum of resistance and more durable nature.

On the rotor 6, at the extreme right end, are gear teeth 27 and on the rotor 5 there is a collar 15 28 having gear teeth 29. In Fig. IV these gear teeth 27, 29 are clearly illustrated. A cage 32, shown more clearly in Fig. V, which carries spur gears 38 is placed in position, as shown in Fig. I, such spur gears 38 being located in mesh between 20 the large gears 29 and 27. Spur gears 38 rotate on stub shafts 30, which are secured in the cage 32 and set a distance from said cage by washers or spacers 34. If preferred, the stub shafts or pins 30 can rotate in the cage 32, as there is more 25 room there for a bearing surface. It is obvious that when spur gears 38 are meshed with the planetary gears 27 and 29 and the rotor 5 is rotated clockwise, that the rotor 6 would be rotated counter-clockwise. Blades 7 on the rotor 5 are 30 placed so that when gas or steam passes through, the turbine 5 will rotate clockwise. In like manner the blades 8 of the rotor 6 are at such an angle that gas passing through the turbine exerts an effort in rotation on the rotor 6 that is counter-clockwise. As the driving effort on the turbine is 35 exerted on the shaft 1, the resistance to the load will absorb the power from the rotor 5 and have a tendency to slow its rotation. However, the design of the turbine being such that, the resistance being equal, both rotors 5, 6 will revolve at equal speed but in opposite directions, the tendency for rotor 6 to run at high speed being offset by spur gears 38 which transmit equal resistance from rotor 5 to rotor 6, and gears said rotors so 40 that they must rotate at approximately equal speed, while the driving force of rotor 6 is transferred to that of rotor 5 and the direction is reversed by the spur gears 38 so that the effective effort of both said rotors is conveyed to shaft 1 rotating clockwise.

An exhaust manifold 36 is placed over the circular exhaust ring 35 and overlaps the latter by a peripheral projection 37, and to which either piston rings or stuffing boxes may be fitted if desirable to make the joint gas-tight to a high degree, though the pressures at this point be low.

The manifold 11 is made fast to the extension 10 and a gland 39, which screws on the body 41 of the stuffing box 40, is put in place with suitable packing in the space 42. Other means to ensure a gas-tight juncture may be utilized at this point, if desired.

The turbine is now lifted in place, the shaft 1 resting in its supporting bearings 2, on the supports 3, whereupon the cage 32 is made fast to the base 4 by bolts 31. Exhaust pipe 42, which is a part of the exhaust manifold 36, shown in Fig. III, also embodies supports 43 of the cage 32. The various adjustments as to bearings and stuffing 70 boxes previously referred to can now be made.

It is evident that a turbine as above described, with two rotors 5, 6, having alternate rows of blades rotating in opposite directions, will provide a rotor blade area against the inflowing gases that is very much shorter than a conventional 75

rotor, and accordingly a much shorter turbine than where following each row of rotor blades in the ordinary turbine there is a row of stator blades of approximately the same width. In other words the rotor blades 7, 8 in each case function not only as such but also as stator blades. 5

The second object of increasing the efficiency of the turbine is achieved as the friction losses of the stator blades are removed, where in the ordinary turbine stator blades contribute only the 10 straightening of the path of the motive fluid to the desired angle, and the effort exerted against them is either prejudicial or negative as far as being converted into work is concerned.

It may be noted from Fig. VI, applying the 15 parallelogram of forces, the resultant a, c represents the unit velocity expressed linearly. The line a, b , one-half the length of a, d , represents the velocity of the average rotor blade; therefore, a, d represents the velocity of the gas or 20 steam straight through the turbine.

Fig. VII shows the line a', b', b'' which equals a, b in Fig. VI, depicting the same relation, though a', b' and b', b'' that are in opposite directions are of equal length, the velocity of the first rotor, 25 described as a, b in Fig. VI, could be equaled by the velocity of each of the double rotors expressed by a', b' and b', b'' in Fig. VII.

In Fig. VIII there are the rotor blades a and c , and stator blade b , the line a, b, c shows the path 30 of a molecule of gas passing from a rotor blade, to a stator blade, then to a second rotor blade in an ordinary single rotor turbine.

Fig. IX is similar to Fig. VIII, but in which b' is changed to a rotor blade which rotates away 35 from a' and c' demonstrating a path of equal length, i. e., $a, b, c = a', b', c'$, which is obtainable in both Figs. VIII and IX, when a' and c' in Fig. IX move one-half as fast as a, c provided b' moves in the opposite direction at a 40 speed equal to that of a' and c' .

Fig. X shows molecules of gas m' and m^2 in a line from a rotor blade, with m impinging on the blade 2. Dotted blade 2' shows its position when reached by m^2 . Rotor blade 3, travelling in the 45 opposite direction shows the subsequent position of m' when they contact, and dotted blade 3' its position when reached by m^2 . In these figures it is assumed the gas or steam until deflected, travels in a straight line and with twice the velocity 50 of the rotor blades, and the angle of incidents is equal to the angle of refraction, with the correction of the angle of refraction due to the moving blades.

There is a difference in the reaction of a mole- 55 cule of gas or steam on striking a stationary stator blade between that of one striking a moving rotor blade. The reaction in a line normal to the blade being the difference in velocities of the molecule and blade in the same direction. 60 Therefore, to equal this effect at a given gas or steam speed against a stator, the said speed along the normal line would have to be increased by the rotor speed in the same direction.

Accordingly, higher gas velocities are obtain- 65 able when the stator blades move away from the gas or steam like rotor blades, or all blades have a dual function, serving as both stator and rotor blades.

Having thus described my invention, what I 70 claim is:—

1. In an axial flow turbine the combination of inner and outer concentric flaring rotors each embodying circumferential rows of respectively-alternating reversely-directed blades, said inner 75

5   rotor being rigidly secured on the turbine shaft and embodying an annular exhaust chamber at the larger end for coaction with a stationarily mounted outlet manifold, said outer rotor being
10   antifrictionally mounted for revolution in a reverse direction about the inner rotor, whereby all of the blades function in the dual capacity of impact and reaction elements, and planetary gearing including toothed rings with an individual cage-like structure supporting intermeshing spur gears about the annular exhaust end of the turbine, said gears operatively coordinating the rotors for opposed revolution at substantially equal speeds.

15   2. The combination of claim 1 wherein one of the rotors is antifrictionally journaled by a ball thrust bearing at one end on the inner rotor, and

at its other end by a similar bearing associated with the motivating medium inlet manifold.

3. The combination of claim 1 wherein the outer rotor is antifrictionally journaled about an exhaust manifold integral with the inner rotor and at its other end by a similar bearing about the motivating medium inlet manifold, and means whereby said rotors may be axially adjusted and secured in coactive relation.

4. The combination of claim 1 wherein the 10 planetary gearing comprises gear rings secured in an annular portion of the outer rotor and to the exterior of an annular exhaust manifold extension of the inner rotor, and the cage-like structure embodies a closure for the exhaust 15 manifold with integral outlet connections.

FRANCIS M. BROOKE.
